UNITED STATES PATENT OFFICE.

GEORGE T. MCLEOD, OF DEDHAM, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

TOP-LIFT SCALLOPER OR CONCAVER.

1,107,820.

Specification of Letters Patent.

Patented Aug. 18, 1914.

Application filed October 27, 1909, Serial No. 524,951. Renewed May 9, 1913. Serial No. 766,656.

To all whom it may concern:

Be it known that I, GEORGE T. MCLEOD, a citizen of the United States, residing at Dedham, in the county of Norfolk and State of Massachusetts, have invented an Improvement in Top-Lift Scallopers or Concavers, of which the following description, in connection with the accompanying drawings, is a specification, like letters on the drawings representing like parts.

The invention herein to be described relates to machines for cutting the breast portion of boot and shoe heels and more particularly for scalloping or concaving the breast edge of the toplift.

The aims and purposes of the present invention are to provide a machine of the general type mentioned which shall be simple in construction, efficient in operation, and wherein uniformity of product may be attained, all as will more fully appear from the following description and accompanying drawings of one form of means for carrying the invention into practical effect.

In the drawings:—Figure 1 is a front view of a machine embodying the present invention, the lower portion of the supporting standard being broken away; Fig. 2 is a plan view of the parts shown by Fig. 1, the cutter and part of its shaft being indicated by dotted lines; Fig. 3 is a side view of the machine looking in the direction of the arrow, Fig. 2, the cutter and shaft being omitted; Fig. 4 is a detached view showing the heel supporting plate and breast stops; Fig. 5 is a bottom view of a shoe showing the cut made by the machine at the heel breast; and Fig. 6 is a section on line 6—6, Fig. 3.

Mounted in the suitable bearings 2, Fig. 1, on the column 1 is a knife carrying shaft having secured thereto, as by the screw 3, a knife 4, the cutting blades of which are conically arranged with respect to the shaft, as indicated by dotted lines in Fig. 2. The cutter shaft may be driven from any suitable source of power, as by means of a belt 5 and pulley 6, Fig. 1.

The column 1 near its upper portion has formed thereon suitable ways or guides for sustaining and guiding the work carrying means and its support. In the present form of the invention the guides on the column 1 are preferably formed by means of suitable plates 7 secured to the column by suitable

means and receiving the sliding portion 8 of the bracket 9, the upper portion whereof is provided with a face piece 10 having a slot 11 through which passes the clamping screw 12. The clamping screw 12 is screw-threaded into the bracket or work slide support 13, the connection between the face piece 10 and the bracket or work slide support 13 being provided with guiding means, as for instance the gib 14, whereby upon loosening the clamping screw 12 the bracket or work slide support 13 may be adjusted with respect to the face piece 10 for a purpose that will presently appear.

The bracket or work slide support 13 has at top and bottom the flanges 15 which form suitable guideways for a work slide 16, Figs. 2 and 3, a spring 17, connected at one end to the pin 18 secured to the slide, and at the other end to a suitable pin 19 connected to the bracket or work slide support, tending normally to move the work slide to the right, Fig. 2. Projecting from the bracket 13 is a lug 20, through which is screw-threaded the adjusting stop 21 having a hand wheel 22, the construction being such that, as the work slide is retracted by means of its springs 17, the end thereof will contact with the end of the adjusting stop 21 and limit movement responsive to said springs.

Mounted in a suitable bracket 23, Fig. 1, is an adjusting device, preferably in the form of a threaded pin 24 having a hand wheel 25, and screw-threaded into the bracket 9, the construction being such that, upon rotation of the hand wheel 25, the bracket 9, and hence its face piece 10 and work slide support 13 secured thereto, may be moved in a diagonal direction transversely of the cutter shaft, as will be readily understood.

From the construction thus far described it will be seen that the work slide 16 is supported to slide on the bracket 13 in a direction diagonal to the cutter shaft and substantially parallel to the cutting edges of the cutter blades, as indicated in Fig. 2.

Secured to the work slide is a heel supporting plate 26, the supporting surface of which is at an angle to the cutting edges of the cutter blades, see Fig. 2, so that if the heel be supported upon said heel supporting plate, as indicated at 8 by dotted lines in Fig. 2, the breast line of the heel may be so disposed with respect to the cutting blades

2
that the latter may remove from the breast edge of the toplift a portion thereof to provide the scalloped or concaved effect, as indicated at 27 in Fig. 5.

5 Pivots mounted upon the slide 16, as at 28, 28, Fig. 3, are the breast stop carriers 29, 29, each having secured thereto, as by a screw 30, the recessed plates or boxes 31 which embrace the edge portions of the 10 heel supporting plate 26 at opposite sides thereof, as indicated in Figs. 3 and 4. Adjustably secured to the outer surface portions of the recessed plates or boxes 31 are the heel breast stops 32, 32, each of which 15 is connected adjustably to its recessed plate or box by means of slot and screw connections, as indicated at 33, Fig. 4, the construction being such that the heel breast stops may be properly adjusted with relation to their carrying element.

20 Secured to each of the heel breast stops 32 is a wing portion 34, the rearwardly extending ends of which are widened, Fig. 2, to properly embrace and guide a heel between them and to give an extended bearing for the sides of said heel, as indicated in Fig. 2.

25 Each of the breast stop carriers 29 is preferably formed as an arm and is provided with a pin or roll 35 adapted to engage suitably shaped cam guides or grooves 36 formed on the relatively stationary bracket or work slide support. The cam guides or grooves 36 are preferably formed 30 converging toward the cutter end of the work slide support, as indicated in Fig. 3, so that when the work slide is in its retracted or normal position with its end resting against the adjusting stop 21, Fig. 2, 35 the rolls 35 of the breast stop carriers will be separated, and force the breast gages to occupy positions near to each. If, under these conditions, a heel wider than the 40 distance between the breast stops be moved 45 over the face of the heel plate between the wing portions of the stops, it will cause the breast stops to separate, and the rolls 35, being thus caused to approach each other, travel down the converging guides 36 and 50 cause the work carrying slide to move longitudinally until the breast of the heel meets the breast stops 32, whereupon further movement of the heel over the heel plate and toward the cutter is arrested, the heel 55 being at such time in proper scalloping position.

55 From the construction described it will be noted that the act of placing the heel in working position causes longitudinal movement of the work slide, and that the breast stops, by engagement with the heel breast, act as gaging means for determining not only when the heel is in proper scalloping position on the heel plate, but also the longitudinal movement of the work slide in posi-

tioning a heel nearer to or farther from the end of the cutter. It will be obvious, of course, that the particulars of structure, whereby, as the heel is moved against the breast stops the work slide moves to place 70 the heel in desired position with relation to the cutter, may be variously formed or designed within the true scope of the invention; and it is also obvious that owing to the angular relation of the heel plate and work slide, that movement of the slide might in some cases occur as a result of pushing the heel over the heel plate, and such force might, at times, coöperate with the breast gages as they separate to move the work 80 slide longitudinally, but primarily the act of separating the breast gages effects such movement as the heel is moved to working position.

85 The work slide 16 may be limited in its longitudinal movement toward the end of the cutter and as one means for such limitation, the cam guides or grooves 36 cause the rolls 35 to come together at the juncture of said guides or grooves, though obviously any usual stop might be employed.

90 Since the cutter blades and heel supporting plate are related, as indicated in Fig. 2, it follows that the length of the cut 27, Fig. 5, made in the breast edge of the toplift will 95 depend upon the part of the cutting blades which acts upon the heel when the latter is in its final cutting position, so that should the heel reach its final cutting position at a point nearer the base of the cutting blades, 100 or to the right, Fig. 2, the length of the cut 27 will be less than if such position is reached at a portion of the blades nearer their outer ends, as will be obvious. The longitudinal adjustment of the bracket or 105 work slide support 13, as hereinbefore pointed out, will enable the length of the cut 27 to be varied, as described, and likewise the adjustment of the bracket 9 transversely of the cutter shaft will enable the depth of the 110 cut 27 to be varied without at the same time varying the length.

115 From the described construction as one embodiment of the present invention it will be apparent that the scallop or concave cut 27 formed in the breast edge of the toplift may be variously formed, that is, it may be made longer and deeper or it may be made deeper without being at the same time elongated.

120 The heel supporting plate 26 may preferably have its edge 37, Fig. 4, concave to insure non-interference with the cutting blades; and obviously various changes may be made in the particular means employed 125 as an embodiment of the invention without departing from the true spirit thereof as defined by the claims.

130 In practice the operative adjusts the stop 21 so that when the work slide

is in its normal or retracted position, the breast gages are closer together than the width of the narrowest or smallest heel to be treated. He likewise adjusts the bracket 9, and perforce the work slide support, by means of the adjusting screw 24 and in accordance with the depth of cut desired; and, if necessary, he may move the work slide support or adjust it longitudinally to regulate the length of cut to be made. The operative then places the tread surface of the heel on the heel plate and moves the heel between the wing portions of the breast stops. Since the breast stops 15 are too close together to admit the heel freely, they separate as the heel is pushed to working position and until the breast finally brings up against the hooks of the breast stops. This separating movement of 20 the heel breast gages moves the rolls 35 toward each other with the result that the work slide is moved longitudinally until the heel is arrested by the breast stops, at which time the heel will be in position for 25 treatment. When the heel is removed the spring 17 moves the work slide to initial position against the back stop 21.

What is claimed is:

1. In a machine for scalloping or concaving the breast edge of a toplift, the combination of a rotary cutter, a work slide, a heel supporting plate movable with the work slide, heel breast stops for positioning a heel on the heel supporting plate, and 35 means for causing coincident separating movement of the breast stops and longitudinal movement of the work slide.

2. In a machine for scalloping or concaving the breast edge of a toplift, the combination of a rotary cutter, a work slide, a heel supporting plate carried by the work slide with its heel supporting surface in a plane at an angle to the plane of sliding movement of the work slide, means permitting longitudinal sliding movement of 40 the work slide as the heel of a shoe is forced along the heel supporting plate, and means to engage the heel breast to stop movement of the heel along the heel supporting plate 45 when the heel is in position to be cut.

3. In a machine for scalloping or concaving the breast edge of a toplift, the combination of a cutter, a work slide movable longitudinally in positioning a heel to be 50 cut, a heel supporting plate movable with said work slide, heel breast stops for engaging the breast of a heel to be cut when the heel is in cutting position, and means acting normally to maintain said heel breast 55 stops in close relation and to permit separation thereof and longitudinal movement of the work slide as the heel is moved to working position.

4. In a machine for scalloping or concaving the breast edge of a toplift, the com-

bination of a cutter, a heel plate engaging the heel during the cutting operation, breast gages to engage the breast of the heel to position it, and means for causing relative movement of the cutter and heel plate and 70 permitting separation of said gages as the heel is moved into cutting position.

5. A machine of the character described, comprising in combination, a rotary cutter, a work slide, heel breast gages normally 75 separated a distance less than the width of the heel breast to be treated, and means actuated by movement of the breast gages for moving the work slide.

6. A machine of the character described, 80 comprising in combination, a rotary cutter, a work slide, a heel supporting plate movable with the slide and disposed at an angle to the slide movement, heel breast stops normally separated a distance less than the 85 width of the heel breast to be treated, and means actuated by movement of the breast stops for moving the work slide.

7. A machine of the character described, comprising in combination, a rotary cutter, 90 a work slide movable longitudinally to position the work with relation to the cutter, breast stops normally separated a distance apart less than the width of the heel breast to be treated and each provided with an 95 outwardly flaring wing portion to admit the heel between them, and means for insuring coincident separating movement of the breast stops and longitudinal movement of the work slide.

8. In a machine for scalloping or concaving the breast edge of a toplift, the combination of a cutter shaft, a cutter having outwardly flaring blades secured thereto, a work slide movable longitudinally in a plane parallel to the plane of the cutter blades as they act upon the top lift, a heel supporting plate movable with the slide and disposed in a plane parallel to the axis of the cutting blades, and means to limit the movement of 110 the heel on the heel supporting plate.

9. In a machine for scalloping or concaving the breast edge of a toplift, the combination of a cutter shaft, a cutter having outwardly flaring blades secured thereto, a work 115 slide movable longitudinally in a direction parallel to the length of the cutter blades in putting a heel in position for the action of said blades, a heel supporting plate movable with the slide and disposed at an angle to the cutting blades, means to limit the movement of the heel on the heel supporting plate, and a spring for retracting the work slide in a longitudinal direction.

10. In a machine for scalloping or concaving the breast edge of a toplift, the combination of a cutter shaft, a cutter having outwardly flaring cutting blades, a bracket or work slide support having guideways, a work slide movable longitudinally in said 125 130

4
guideways parallel to the cutting blades, as they pass the toplift cutting position, a heel supporting plate disposed in a plane parallel to the axis of the cutting blades, and breast stops movable into gaging position as the slide is moved longitudinally.

11. In a machine for scalloping or concaving the breast edge of a toplift, the combination of a cutter shaft, a cutter having outwardly flaring cutting blades, a bracket or work slide support having guideways, a work slide movable longitudinally in said guideways parallel to the cutting edges of said blades to carry a heel into position to be cut, a heel supporting plate disposed at an angle to the cutting blades, and means for limiting the movement of the heel on said plate toward the edges of the cutting blades.

12. In a machine for scalloping or concaving the breast edge of a toplift, the combination of a cutter shaft, a cutter having outwardly flaring cutting blades, a bracket or work slide support having guideways, a work slide movable longitudinally in said guideways parallel to the cutting edges of said blades to carry a heel parallel to the edges of said blades into position to be cut, a heel supporting plate disposed at an angle to the cutting blades, and movable with said work slide in a direction parallel to the edges of the cutting blades, and breast stops to position the heel on said supporting plate.

13. In a machine for scalloping or concaving the breast edge of a toplift, the combination of a rotary cutter, a longitudinally movable work slide, a heel supporting plate movable with the work slide to place a heel in cutting position, heel breast stops movable with the slide, and means actuated by movement of the heel into working position for moving the work slide longitudinally.

14. In a machine for scalloping or concaving the breast edge of a toplift, the combination of a rotary cutter, a longitudinally movable work slide, a heel supporting plate movable with the work slide to place a heel in cutting position, heel breast stops movable with the slide, and cam means actuated as the heel is moved into working position for moving the work slide longitudinally.

15. In a machine for scalloping or concaving the breast edge of a toplift, the combination of a bracket or work slide support, a work slide longitudinally movable thereon, breast stops movable with the slide, breast stop carriers pivotally mounted on the slide, and means acting upon said stop carriers to move the slide longitudinally as the breast stops are separated.

16. In a machine for scalloping or concaving the breast edge of a toplift, the combination of a bracket or work slide support, a work slide longitudinally movable thereon, a spring acting normally to retain the slide at one limit of its longitudinal movement,

breast stops movable with the slide, breast stop carriers pivotally mounted on the slide, and means for causing the slide to move longitudinally as the heel is placed in working position.

17. In a machine for scalloping or concaving the breast edge of a toplift, the combination of a rotary cutter having cutting blades, a work slide constrained to movement longitudinally in a single plane by the work as it is placed in operative position, and a heel plate disposed in a plane parallel to the axis of the rotary cutter.

18. In a machine for scalloping or concaving the breast edge of toplifts, the combination of a rotary cutter, a work slide constrained to movement longitudinally in a single plane parallel to the cutting edge of the cutter as the latter acts upon the toplift, and a heel plate secured to the work slide and disposed in a plane substantially parallel to the axis of the rotary cutter.

19. In a machine for scalloping or concaving the breast edge of toplifts, the combination of a rotary cutter, a work slide movable longitudinally in a single plane, a heel plate disposed at an angle to the work slide, and means permitting the work slide to be moved longitudinally in said single plane by movement of the work into operative position with relation to the cutter.

20. In a machine for scalloping or concaving the breast edge of toplifts, the combination of a rotary cutter, a work slide movable longitudinally in a single plane, a heel plate disposed at an angle to the work slide, means permitting the work slide to be moved longitudinally in said single plane by movement of the work into operative position with relation to the cutter, and means for adjusting the slide bodily toward and from the axis of the cutter.

21. In a machine for scalloping or concaving the breast edge of toplifts, the combination of a rotary cutter having flaring blades, a work slide carrying a heel plate and movable longitudinally to position the heel for the action of the cutter, and a spring acting normally to move the slide longitudinally.

22. In a machine for scalloping or concaving the breast edge of toplifts, the combination of a rotary cutter, a work slide movable longitudinally parallel to the blades of the cutter and carrying a heel plate disposed at an angle thereto, a bracket provided with guides for the work slide, and means for adjusting the bracket and guides toward and from the axis of the cutter.

23. In a machine for scalloping or concaving the breast edge of top-lifts, the combination of a cutter to act upon the top-lift edge, a longitudinally movable work slide for moving the heel into operative relation

- opposite the cutter, a heel plate carried by said slide, movable gaging means to determine the movement of the heel toward the cutter, and means for causing conjoint movement of the work slide and gaging means.
24. In a machine for scalloping or concaving the breast edge of toplifts, the combination of a cutter to act upon the toplift edge, a work slide movable longitudinally by movement of the work relative thereto into working relation with the cutter, and gaging means to limit movement of the heel with relation to the work slide as the work slide is moved.
25. In a machine for scalloping or concaving the breast edge of toplifts, the combination of a cutter to act upon the toplift breast edge, a work slide movable longitudinally by movement of the work relative thereto into working relation with the cutter, and a heel plate disposed upon the work slide against which the heel bears when in working position.
26. In a machine for scalloping or concaving the breast edge of toplifts, the combination of a cutter to act upon the toplift breast edge, a work slide movable longitudinally by movement of the work relative thereto, a heel plate disposed upon the work slide against which the heel bears when in working position, and a gage acting jointly to limit the movement of the heel and determine the movement of the slide.
27. In a machine for scalloping or concaving the breast edge of toplifts, the combination of a cutter to act upon the toplift breast edge, a work slide movable longitudinally, means for moving the work slide longitudinally as the heel is moved relative thereto, a heel plate disposed upon the work slide against which the heel bears when in working position, and a spring to return the slide to initial position.
28. In a machine for scalloping or concaving toplifts, the combination of a cutter to act upon the breast edge of the toplift, a longitudinally movable slide for positioning the heel with respect to the cutter, and means for imparting longitudinal movement to the slide by movement of the heel relative thereto to working position.
29. In a machine for scalloping or concaving toplifts, the combination of a cutter to act upon the breast edge of the toplift, a work support for positioning the heel for the action of the cutter, and gaging means for determining the position of the heel, said gaging means having flaring wing portions to admit the heel and guide it to the gaging

means, and said gaging means acting to move the work support as the heel is moved relative to the work support.

30. A machine for removing a scallop of material from the edge of a heel comprising a frusto conical cutter, and means for guiding the heel against the cutter and determining in accordance with the size of the heel the diameter of the cutter with which the heel shall contact.

31. A machine for removing a scallop from the edge of a heel comprising a frusto conical cutter and means controlled by the width of the heel for determining the portion of the cutter with which the heel shall contact.

32. In a machine of the class described, the combination of a rotary cutter having varying diameters, and means controlled by the size of the work for determining the diameter of the cutter which shall contact with the work.

33. In a machine of the class described, the combination of a frusto-conical cutter and gages controlled by the width of the heel for presenting a wide heel to a portion of the cutter having a large diameter and a narrow heel to a portion of the cutter having a small diameter.

34. In a machine of the class described, the combination of a frusto-conical cutter and gages constructed and arranged to be controlled by the width of the heel for presenting a heel to that part of the cutter which corresponds in diameter to the size of the heel.

35. A machine for producing a scallop in the edge of a heel comprising a continuously actuated cutter to which the heel is presented and means controlled by the width of the heel for determining the extent of the scallop.

36. In a machine of the class described, the combination of a rotary cutter having varying diameters, and means controlled by the size of the work for determining the length of the cut to be made by the cutter.

37. In a machine of the class described, the combination of a rotary cutter and means controlled by the work for determining the section in the length of the cutter that is to act upon the work.

In testimony whereof, I have signed my name to this specification, in the presence of two subscribing witnesses.

GEORGE T. MCLEOD.
